Oscar Geier

UNITED STATES PATENT OFFICE.

CHARLES BERBERICH, OF WATERBURY, CONNECTICUT.

POCKET-LIGHTER.

1,289,614.

Specification of Letters Patent. Patented Dec. 31, 1918.

Application filed January 14, 1918. Serial No. 211,781.

To all whom it may concern:

Be it known that I, CHARLES BERBERICH, a citizen of the United States, resident of Waterbury, county of New Haven, and State 5 of Connecticut, have invented certain new and useful Improvements in Pocket-Lighters, of which the following is a specification.

This invention relates to improvements in pocket lighters, and has as its special object 10 the provision of means whereby currents of air are prevented from coming in contact with the flame when the article is in use, thereby providing against its untimely extinguishment.

15 A further object is to provide such devices in forms which may either be operated manually or may be placed upright upon any level foundation during their operation.

These and other like objects are attained 20 by the novel construction and combination of parts hereafter described and shown in the accompanying drawings, forming a material part of this disclosure and in which:—

25 Figure 1 is a side elevational view of a lighter made in accordance with the invention.

Fig. 2 is a similar view of the same, the guard element being extended.

30 Fig. 3 is a front view of the lighter as extended.

Fig. 4 is a fragmental sectional view drawn to a further enlarged scale, illustrating the structure of the guard element.

The invention is comprised of a tubular 35 casing 10, is mounted upon a plate 11, the casing being adapted to contain combustible fluid, as alcohol, gasolene or the like, the gases of which rise to the wick 12, in the manner described in a co-pending application, as is also the method of lighting and 40 construction of the lighter body.

Extending downward from the casing 10 upon opposite sides are pins 15, engaging in open slots 16, formed longitudinally in a 45 tubular sleeve 18, the same being slidably fitted to the exterior of the casing 10, which is normally covered at its upper portion by a cap 20, carrying a bar of pyrophoric material 21, in such manner that by removing 50 the cap and properly manipulating the same, the wick 12 may be ignited by contact of the

pyrophoric material with the sharp edge of a ring 22, at the top of the casing.

Formed at the top of the tubular sleeve 16 is an annular flange 25 upon which is 55 mounted a cylindrical element 26, of a telescopic hood, comprising other cylindrical elements 28 and 30, each having flanges 27 and 29 respectively, the edges of the flanges engaging in corresponding annular recess 60 formed within the cylinders at the top and bottom of each so as to hold the parts firmly either when extended or folded. The outer cylinder 30 is provided with a cover containing an opening 32, permitting the hood to be 65 drawn down over the casing and also allowing the end of a cigar to be entered so as to ignite the same direct from the flames issuing from the wick 12, or if preferred, the cigar may be entered through an opening 35 70 formed partially in the telescopic elements 27 and 28, when these elements are extended as indicated in Figs. 2 and 3.

Thus it is possible to readily light a cigar even in a violent wind, and at the same time, 75 the wind guard, when in a folded or collapsed position, occupies but a relatively small space so that the implement is not bulky or inconvenient of use.

Having thus described my invention, what 80 I claim as new and desire to secure by Letters Patent is:—

1. In a lighter, the combination with a cylindrical casing adapted to contain liquid combustibles, a wick therein, means for igniting said wick, and a cap adapted to be secured over said casing, of a sleeve slidably arranged on said casing, means for limiting the motion of said sleeve therewith, a plurality of telescopic elements engaged with 85 the upper end of said sleeve and means whereby said elements may be held in an extended or collapsed position, said telescopic elements having openings receptive of the article to be ignited. 90

2. In a lighter, the combination with a hollow cylindrical casing adapted to contain inflammable liquid, a wick extending outward at one end, a cap normally covering said wick, a steel ring carried at the upper 95 end of said casing, means combined with said cap adapted to produce sparks whereby 100

said wick may be ignited, a cylindrical sleeve
slidably engaged upon the outer surface of
said casing, means for limiting the longitudi-
nal movement thereof, a plurality of tele-
scopic guard elements slidably engaged with
5 said sleeve, means permitting said elements
said sleeve, means permitting said elements
to be extended or retracted, and held in an

adjusted position, said telescopic elements
being adapted to receive an article to be ig-
nited, all substantially as shown and de- 10
scribed.

In testimony whereof I have affixed my
signature.

CHARLES BERBERICH.
